VALVE STEM CLAMP

Sam J. Kosik, Jr., and Frank B. Robb,
Mayfield Heights, Ohio

Filed May 23, 1960, Ser. No. 60,701

Term of patent 14 years

(Cl. D90—20)

FIG. 1

FIG. 2

FIG. 3

FIG. 4

FIGURE 1 is a top plan view of a valve stem clamp embodying our new design.

FIGURE 2 is an end elevation thereof.

FIGURE 3 is a side elevation thereof.

FIGURE 4 is a bottom plan view thereof.

We claim:

The ornamental design for a valve stem clamp, substantially as shown.
